UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING-RELEASE RIGGING.

1,184,116.

Specification of Letters Patent. Patented May 23, 1916.

Application filed December 28, 1915. Serial No. 69,042.

To all whom it may concern:

Be it known that I, ISAAC H. MILLIKEN, a citizen of the United States, residing at Aspinwall, in the county of Allegheny and State of Pennsylvania, have invented certain new and useful Improvements in Coupling-Release Rigging; and I do hereby declare the following to be a full, clear, and exact description of the invention, such as will enable others skilled in the art to which it appertains to make and use the same.

My invention relates to the construction of release rigging mechanism for actuating the knuckle locking means of car couplers, and is designed to be especially applicable to car couplers in which the coupler head is pivotally connected to the coupler stem or shank so as to be capable of lateral swinging movements with respect to the latter.

The principal object of the invention is to provide such a coupler with an efficient release rigging of simple form consisting of compactly arranged parts which may be placed together within a very small compass, thereby providing increased clearance for the installation of steam and air pipes, safety chain anchorages, and such other devices as are usually mounted on the ends of cars in proximity to the coupler, and thus permitting the couplers when the cars are on curved track to swing sidewise to their full extent without interfering with any neighboring devices.

A further object of the invention is to so form and combine the parts of the release rigging as to reduce the number of fastening devices for maintaining the parts in assembled relation, thereby increasing the durability of the mechanism and diminishing its liability of becoming accidentally disassembled when in service.

Generally stated, the principal objects above noted are effected in a device involving a coupler head and its knuckle locking means, a coupler stem and means for pivotally connecting said head and stem, by combining with such devices mechanism for moving the knuckle locking means to unlocked position, such lock actuating mechanism being supported beneath the

coupler head and involving a bracket or suitable support which is secured to the head and is movable therewith, a member which is pivotally mounted on the bracket and is adapted to engage and actuate the knuckle locking means, and an uncoupling lever which is adapted to actuate the said pivotally mounted member, the said bracket being provided with arms between which the said pivotally mounted member extends, and the uncoupling lever being arranged to engage the said pivotally mounted member between the arms of the bracket.

In the drawings which illustrate the preferred embodiment of my invention, the scope whereof is pointed out in the claims; Figure 1 is a front elevation of a car coupler combined with a release rigging embodying the invention. Fig. 2 is a plan view of the coupler head and portions of the release rigging mechanism shown in Fig. 1. Fig. 3 is a side elevation of the release rigging, showing its relation to the coupler, portions of the uncoupling levers being omitted. Fig. 4 is a detail vertical section on the line 4-4, Fig. 3. Fig. 5 is a detail vertical section on the line 5-5, Fig. 3, also showing in dotted lines the position of one of the uncoupling levers when being brought into assembled relation with the pivotally mounted lock-actuating member. Fig. 6 is a detail perspective view of the bracket which forms the means for supporting the pivotally mounted lock-actuating member. Fig. 7 is a detail perspective view of the pivotally mounted lock-actuating member. Fig. 8 is an inverted plan view of the bracket; and Fig. 9 is a detail sectional view on the line 9-9, Fig. 1, showing a preferred form of keeper that is employed for supporting the outer ends of the uncoupling levers.

In the drawings, 1 indicates a coupler head having a knuckle 2 and a vertically movable lock 3 for retaining the knuckle in locked position. The coupler head is pivotally mounted on the coupler stem 4 by a vertically extending pivot pin 5, which is provided at its lower end with a polygonal head 6 and is threaded at its upper end to 100

receive a nut 7 by which it is retained in assembled relation with said coupler head and stem.

Mounted beneath the coupler head so as to partake of the swinging movements thereof, and having an axis of rotation to the rear of the pivot pin 5, is a lock actuating member 8 whose forward end engagingly overlaps that portion of the lock 3 which projects downwardly outside the coupler head. The means for forming a pivotal support for the lock actuating member 8 may be secured to the coupler head 1 and preferably is fashioned as a bracket 9 having a pair of rearwardly extending parallel arms 10. As shown more particularly in Figs. 3 and 6 the arms 10 of the bracket are preferably of hook-like form, being open at the top and having curved seats forming supporting bearings for the laterally extending pintles or journals 11 with which the member 8 is provided at its rear end. The bracket 9 is preferably secured to the coupler head through the instrumentality of the pivot pin 5. To this end the bracket may be provided toward its forward end with an opening 12 which is adapted to receive the said pivot pin, and is also provided adjacent the said opening with recesses 13 which are adapted to receive corresponding lugs 14 with which the coupler head 1 is provided adjacent to the pivot pin opening in said head. By the engagement of the lugs 14 with the bracket 9, the latter is caused to turn with the coupler head, as will be readily understood. On its under side the bracket 9 is recessed, as at 15, to receive the head 6 of the pivot pin 5, the vertical walls of said recess being preferably adapted to engage corresponding vertical faces of the head 6 so as to prevent rotation of the pivot pin 5 with respect to said bracket and, consequently, with respect to the coupler head 1 also. It will be seen that the pivot pin 5 by which the coupler head 1 and coupler stem 4 are pivotally connected thus also performs the function of a bolt for securing the bracket 9 to the coupler head.

At its rear end the lock actuating member 8 is provided between its journals on pintles 11 with a pocket or recess 16 which is adapted to receive upwardly extending inner ends 17 of the uncoupling levers or members 18 that respectively extend in opposite directions toward the sides of the car. The recess 16 is preferably open at the top as well as at the sides, as well shown in Figs. 3, 5, and 7. The proximate ends 17 of the uncoupling levers 18 are supported upon the lower wall 19 of the recess 16 that is formed in the lock actuating member 8, the said wall 19, when the parts are in assembled position, being sufficiently far below the lower faces of the hooked arms 10 of the bracket 9 to permit the ends of the uncoupling levers to

be introduced into the said recess 16, but being sufficiently near the said lower faces of the bracket arms 10 to cause the uncoupling levers 18 to come into engagement with said arms and thus prevent any such upward movement of the rear end of the lock actuating member 8 as would lead to the accidental shape of the journals or pintles 11 from their bearings in the hooked members 10. The uncoupling levers 18 thus serve as a means for locking the member 8 in assembled position with respect to its supported bracket 9, and special auxiliary means for such purpose may therefore be omitted.

As shown more particularly in Figs. 3 and 5, the recess 16 is formed with downwardly diverging transverse walls, the recess being thus somewhat wider at the bottom than at the top. By this means sufficient clearance is afforded to permit one of the uncoupling levers 18 to be rotated to actuate the member 8 and unlock the coupler without causing a rotation of the other uncoupling lever, and also to permit the uncoupling lever to return to normal position independently of a corresponding movement of the lock actuating member 8.

As indicated in dotted lines in Fig. 5, the uncoupling levers are entered in the recess 16 of the member 8 by elevating their outer ends, inserting the inner ends thereof into the recess, and then lowering their outer ends and inserting them in the supporting keepers 20 which are mounted on the car near the sides thereof. Each of the keepers 20 is preferably open on one side, said opening being adapted to be closed by a removable closure which is preferably in the form of a cotter 21.

When either of the uncoupling levers 18 is rotated in the proper direction the bent inner end 17 thereof causes a corresponding rotation of the lock actuated member 8, whose outer end, coming into contact with a portion of the lock 3, as for example a shoulder 22, thereon, causes said lock to move upwardly to unlocked position.

I claim:

1. In a device of the character indicated, the combination with a coupler and its knuckle locking means, of mechanism for moving said knuckle locking means to unlocked position, said mechanism involving a bracket, a member pivotally mounted on said bracket and adapted to actuate said knuckle locking means, and an uncoupling lever for actuating said pivotally mounted member, said uncoupling lever being supported by said pivotally mounted member and constituting means for maintaining said pivotally mounted member in assembled position with respect to said bracket.
2. In a device of the character indicated, the combination with a coupler and its

knuckle locking device, of mechanism for moving said knuckle locking device to unlocked position, said mechanism involving pivotally mounted means adapted to actuate said knuckle locking device, means forming a support for said pivotally mounted means, and an uncoupling lever for actuating said pivotally mounted means, said uncoupling lever being supported by 5 said pivotally mounted means and serving to maintain said pivotally mounted means in assembled relation with respect to its said supporting means.

3. In a device of the character indicated, 15 the combination with a coupler and its knuckle locking means, of mechanism for moving said knuckle locking means to unlocked position, said mechanism involving a bracket, a member pivotally mounted on 20 said bracket and adapted to actuate said knuckle locking means, and a plurality of uncoupling levers either of which is adapted to independently actuate said pivotally mounted member, said uncoupling levers 25 constituting means for maintaining said pivotally mounted member in assembled relation with respect to said bracket, and said pivotally mounted member being pivotally connected to said bracket by means independent of said uncoupling levers.

4. In a device of the character indicated, 35 the combination with a coupler head and its knuckle locking means, a coupler stem and means for pivotally connecting said head and stem, of mechanism for moving said knuckle locking means to unlocked position, said mechanism being supported beneath said head and involving a bracket which is secured to said head and is movable 40 therewith, a member which is pivotally mounted on said bracket and is adapted to actuate said knuckle locking means, and an uncoupling lever which is adapted to actuate said pivotally mounted member, said bracket 45 being provided with arms between which said pivotally mounted member extends, and said uncoupling lever engaging said pivotally mounted member between said arms of the bracket, said uncoupling lever being 50 pivotally connected to said pivotally mounted member so as to permit said uncoupling lever to change its angular relation to said pivotally mounted member.

5. In a device of the character indicated, 55 the combination with a coupler and its knuckle locking means, of mechanism for moving said knuckle locking means to unlocked position, said mechanism involving a bracket, a member which is pivotally mounted on said bracket and is adapted to actuate said knuckle locking means, and a plurality of uncoupling levers either of which is adapted to actuate said pivotally mounted member, said pivotally mounted member being provided with a recess which

receives the adjacent ends of said uncoupling levers and serving to support the adjacent ends of said levers.

6. In a device of the character indicated, 70 the combination with a coupler and its knuckle locking device, of mechanism for moving said knuckle locking device to unlocked position, said mechanism involving pivotally mounted means adapted to actuate said knuckle locking device, means forming 75 a pivotal support for said pivotally mounted means, an uncoupling lever for actuating said pivotally mounted means, and a keeper in which said uncoupling lever is revolvably mounted and by which it is supported, said 80 uncoupling lever being also supported by said pivotally mounted means and serving to prevent the latter from becoming accidentally disassembled, and said keeper having an opening and a removable closure 85 therefor whereby said lever may be assembled with and disassembled from said keeper by the removal and replacement of said closure.

7. In a device of the character indicated, 90 the combination with a coupler and its knuckle locking means, said coupler having a head and a stem which are pivotally connected, of mechanism for moving said knuckle locking means to unlocked position, 95 said mechanism involving pivotally mounted means adapted to actuate said knuckle locking means, a support for said pivotally mounted means, said support extending rearwardly of the point of pivotal connection 100 of said head and stem and being movable with said head, and an uncoupling lever for actuating said pivotally mounted means, said uncoupling lever being supported by and interlocking with said pivotally mounted means beneath said support, whereby said uncoupling lever is maintained in assembled 105 relation with said pivotally mounted means.

8. In a device of the character indicated, 110 the combination with a coupler-head, knuckle and its knuckle locking means, of mechanism for moving said knuckle locking means to unlocked position, said mechanism involving a bracket which is movable with the coupler head, a member pivotally mounted on said bracket and adapted to actuate said knuckle locking means, and an uncoupling lever which is adapted to actuate said pivotally mounted member, said 115 uncoupling lever constituting means for maintaining said pivotally mounted member in assembled relation with respect to said bracket and being adapted to return to normal position independently of and after having actuated said pivotally mounted member.

9. In a device of the character indicated, 120 the combination with a coupler and its knuckle locking means, of mechanism for moving said knuckle locking means to un- 125

locked position, said mechanism involving pivotally mounted means for actuating said knuckle locking means, a support for said pivotally mounted means, and an uncoupling device for actuating said pivotally mounted means, said uncoupling device being supported by and interlocking with said pivotally mounted means and being adapted

to return to normal position independently of and after having actuated said pivotally mounted means and constituting means for maintaining said pivotally mounted means in assembled relation with said support.

In testimony whereof I affix my signature.

ISAAC H. MILLIKEN.
